Primary Examiner — Kelley Donnelly(74) *Attorney, Agent, or Firm* — Thompson Coburn LLP;
Matthew Himich(57) **CLAIM**

The ornamental design for an adjustable shelf divider for display of bagged food items, as shown and described.

DESCRIPTION

FIG. 1 is a perspective view of the design in an extended configuration, showing the left front and top sides thereof. FIG. 2 is a front view of the design.

FIG. 3 is a rear view of the design.

FIG. 4 is a left side view of the design.

FIG. 5 is a right side view of the design.

FIG. 6 is a top view of the design.

FIG. 7 is a bottom view of the design; and,

FIG. 8 is a perspective view of the design in a partially retracted configuration, showing the left front and top sides thereof.

1 Claim, 4 Drawing Sheets(56)
